UNITED STATES PATENT OFFICE.

BENJAMIN S. PUTTS, OF ERIE, PENNSYLVANIA.

ELECTRIC-SWITCH MECHANISM.

1,192,346.

Specification of Letters Patent. Patented July 25, 1916.

Application filed August 9, 1915. Serial No. 44,481.

To all whom it may concern:

Be it known that I, BENJAMIN S. PUTTS, a citizen of the United States, residing at Erie, in the county of Erie and State of Pennsylvania, have invented certain new and useful Improvements in Electric-Switch Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to combination electric switches. Switches of this character are particularly desirable for controlling the ignition of the motors of vehicles, for the purpose of preventing unauthorized use of such vehicles; but such switches may be used with advantage in other electric circuits where it is desirable to prevent unauthorized use of current.

The object of my invention is to provide the ordinary lever switches with a cut-out mechanism controlled by a plurality of push pins, so that it is necessary to know what combination of push pins and the sequence of the same, in order to close the cut-out mechanism so that the switch lever will, when operated, close the circuit.

The features of my invention are herein-after described and pointed out, and are illustrated in the accompanying drawings in which:

Figure 1, is a front elevation of a combination switch embodying my invention. Fig. 2, is a rear elevation of the same with the back plate removed. Fig. 3, is a transverse section of the same on the line $x-x$ in Fig. 2. Fig. 4, is a top side view of one part of the mechanism of my invention. Fig. 5, is an underside view of another part of the mechanism of my invention. Fig. 6, shows the center-post mechanism of my invention, disjoined and removed therefrom.

In these drawings A, indicates the body or case of my invention, which is circular in form, and made preferably of non-conducting material, and provided with annular flanges, A' and A'' , on the rear side thereof, so that there is an annular space A^3 , between the flanges A' and A'' , and a circular space A^4 , within the flange A'' . Centrally in the space A^4 , I place a square post B, having a longitudinal screw threaded hole there-

through, and which is provided with a round extension B' , which extends through a central hole in the case A, and is secured therein by means of a screw b . The opposite end of the post B is also provided with a round extension B^2 for the purpose hereinafter set forth. Upon the square post B, I place a disk C, which is provided with a cylindrical hub C' , having a square central opening therethrough to slidably fit the square post B. The disk C, is also provided on its upper side with a series of annular ratchet teeth c . Under the disk C, I place springs C^2 , to normally maintain the disk C, in a raised position, and through a longitudinal slot in the hub C' , of the disk, I secure a stud-pin C^3 , in the square post B, which serves to limit the upward movement of the disk C.

Rotatably mounted upon the hub C' , of the disk, I place a wheel D, which is provided on its under side with a series of annular ratchet teeth D' , which intermesh with the ratchet teeth c , on the disk C. The wheel D, is provided with a hub having an in-turned flange D^2 , which lies over the end of the hub C' , of the disk C, and fits the round extension B^2 , on the post B. I then screw the part B^3 , of the center-post (see Fig. 6) into the square post B which secures the disk C, and wheel D, in place on said post, the stud pin C^3 , extending outward through a short circumferential slot in the wall of the hub of the wheel D, permitting of a limited rotary movement of said wheel. The wheel D, is provided on its periphery with teeth d , d' , and d'' , for the purpose hereinafter described. Upon the hub of the wheel D I place a spring D^4 , one end of which is secured to a stud pin d^2 , and the other end thereof to the stud pin C^3 , secured in the square post B, and operates to move the wheel D, in one direction. Pivoted upon the flange A^2 , there is a rocking lever E, having a bifurcated end extending over the wheel D, and a hooked end extending over the space A^3 , between the flanges A' and A'' , so as to contact with an electric terminal T, secured on the flange A. Mounted in the case A, there is a rocking post G, which is provided with an eccentric projection g , on the end thereof adapted to engage the hooked end of the lever E, when the same has been operated as hereinafter described. For operating the lever E, I secure an insulated stud pin E' , in the wheel D, so that it will project between the horns of the bifurcated end

of the lever E. On the outer end of the post G, I secure a switch lever G', by which the post G, can be operated.

In suitable openings in the flanges A' and A², I place radial pins 1, 2, 3, 4, 5, 6, 7 and 8, which are provided with springs g', one end of which is inserted through transverse holes in said pins inside of the flange A, and the other end of said springs being inserted under said pins, and engaging the flange A², said springs operating to force the pins outward, limit their outward movement and also prevent said pins from revolving in their holes. The inner ends of the pins 3, 6 and 8, are adapted to engage the teeth d, d', and d², on the wheel D, when pushed in consecutively and are made with axial inclined faces g², to co-incide with the inclined surfaces of said teeth, and the inner ends of the pins 1, 2, 4, 5 and 7, are provided with radial, inclined faces g², adapted to slide over the upper side of the disk C, and force it downward away from the wheel D, when any of said pins are operated.

In operation the lever G', is pushed into the position shown in full lines in Fig. 1, so that it contacts with the screw b, then the pin 3, is pushed in, the inner end thereof contacting with the tooth d, on the wheel D, and causing it to rotate far enough to put the tooth d', into position to be engaged by the pin 6. The pin 6, is then pushed inward, which continues the movement of the wheel D, sufficiently to place the tooth d², to be engaged by the pin 8, during which two movements the insulated stud pin E', has moved across the space between the horns of the bifurcated lever E. The pin 8, is then pushed inward and engages the tooth d², which forces the wheel D, to travel far enough to cause the stud pin E', to swing the lever E, so that its hooked end will enter between and contact with the eccentric extension g, on the post G, and the terminal F, secured on the flange A'. The circuit is thus completed through the central post, screw b, lever G', post G, eccentric extension g, thereon, the hooked end of the lever E, and terminal F, which can be broken by swinging the lever G', off of the screw b, as shown by broken lines in Fig. 1, which causes the eccentric extension on the post G, to move backward from the hooked end of the lever E, and thus break the circuit. When it is not desired to disturb the combination set by the operation of the pins 3, 6, and 8, hereinbefore described. But when it is desired to break said combination, one has only to push inward on any one of the pins 1, 2, 4, 5 or 7, which will force the disk C, downward, thereby parting the ratchet teeth c and D', which permits the spring D⁴, to move the wheel D, back to its starting point, and the insulated stud-pin E', thereon, swings the lever E, so that its hooked end

is out of contact with the terminal F, so that if the switch lever G', is again moved over into contact with the screw b, the circuit remains broken between the eccentric projection g, on the post G, and the terminal F, which can only be closed by the operation of the combination as before described.

While I have shown the case A, as constructed of non-conducting material, it is obvious that other material can be used if desired, by the employment of proper insulation, and while I have shown and described a convenient mechanism for breaking the circuit within the case, it is obvious that many other forms of mechanism can be employed without departing from the spirit of my invention: but

What I claim as new and desire to secure by Letters-Patent, is:—

1. In a device of the class described, an electric circuit, a swinging lever adapted to make and break said circuit, a central post, a wheel mounted on said post, teeth on said wheel, means on said wheel to operate said lever, spring-pressed pins adapted to engage the teeth and operate said wheel in one direction, a spring to operate said wheel in the opposite direction, ratchet mechanism to prevent the backward movement of said wheel, and other spring-pressed pins to operate said ratchet mechanism, substantially as set forth.

2. In a device of the class described, a circular case, a central terminal post secured thereon, a spring-pressed disk slidably and non-rotatably mounted on said post, ratchet teeth on said disk, a wheel rotatably supported on said post, means on said wheel to engage said ratchet teeth on said disk, a spring to move said wheel in one direction, teeth on said wheel having inclined sides, an electric terminal secured to said case, means operable by said wheel to make and break said circuit, and radial spring-pressed pins slidably mounted in said case, some of which are adapted to engage said teeth on said wheel, and some of which are adapted to engage said ratchet disk, substantially as described.

3. In a device of the class described, a circular case, a central post secured thereon, a spring-pressed disk non-rotatably and slidably mounted on said post, ratchet teeth on said disk, a rotatable wheel supported by said post, teeth on said wheel, means on said wheel to engage the ratchet teeth on said disk, a stud-pin on said wheel, an electric terminal secured to said case, a swinging lever pivoted to said case and adapted to be engaged by said stud-pin, and the opposite end of said lever adapted to contact with said terminal, and radial, spring-pressed pins mounted in said case, some of which are adapted to engage the teeth on said wheel for the purpose of giving limited ro-

- tation to said wheel, and others of said pins adapted to engage said disk to move it away from said wheel to disengage said ratchet teeth, substantially as described.
- 5 4. In a device of the class described, a circular plate, annular flanges thereon, a terminal post secured in said plate, a terminal secured on one of said flanges, a rocking post pivoted in said plate, an eccentric shoulder on said post, a switch lever adapted to rotate said rocking post and contact with said terminal post so that said eccentric extension will be moved toward the terminal secured on said peripheral flange, a swinging lever pivoted on one of said flanges, and adapted to bridge the space between said eccentric shoulder and the terminal secured on the peripheral flange, a wheel mounted on said central post, a spring to move said wheel in one direction, teeth on said wheel, radial spring-pressed pins to engage said teeth and move said wheel in the opposite direction, ratchet mechanism to prevent backward movement of said wheel, means on said wheel to engage and operate said swinging lever to close said electric circuit, other spring-pressed pins to operate said ratchet mechanism, substantially as set forth.
- 10 5. In a device of the class described, a circular front plate of non-conducting material, a peripheral flange thereon, a central post secured in said plate adapted to act as an electric terminal, a rocking post pivoted in said plate, a switch lever secured on said post and adapted to contact with said central post to form a connection from said central post to said rocking post, an eccentric projection on the inner end of said rocking-post, an electric terminal secured to said plate in spaced relation to said eccentric projection, a swinging lever pivoted upon said plate and adapted to move into the space between said projection and said terminal and contact with both, a wheel supported on said central post, means to limit the movement of said wheel, a spring to operate said wheel in one direction, means on said wheel to engage and operate said swinging lever, inclined projections on said wheel, a plurality of spring-pressed pins mounted in said flange and adapted to engage consecutive teeth on said wheel when pressed in a prescribed order to move said wheel sufficiently to cause said swinging lever to close the break in the circuit between the eccentric projection and its adjacent terminal, so that the circuit will be completed from the central post to the terminal on said flange, mechanism to prevent said wheel from moving backward and radial spring-pressed pins mounted in said flange adapted to release said ratchet mechanism, substantially as set forth.
- 15 6. In a device of the class described, a circular front plate of non-conducting material, a peripheral flange thereon, a central post secured in said plate adapted to act as an electric terminal, a rocking post pivoted in said plate, a switch lever secured on said post and adapted to contact with said central post to form a connection from said central post to said rocking post, an eccentric projection on the inner end of said rocking-post, an electric terminal secured to said plate in spaced relation to said eccentric projection, a swinging lever pivoted upon said plate and adapted to move into the space between said projection and said terminal and contact with both, a wheel supported on said central post, means to limit the movement of said wheel, a spring to operate said wheel in one direction, means on said wheel to engage and operate said swinging lever, inclined projections on said wheel, a plurality of spring-pressed pins mounted in said flange and adapted to engage consecutive teeth on said wheel when pressed in a prescribed order to move said wheel sufficiently to cause said swinging lever to close the break in the circuit between the eccentric projection and its adjacent terminal, so that the circuit will be completed from the central post to the terminal on said flange, mechanism to prevent said wheel from moving backward and radial spring-pressed pins mounted in said flange adapted to release said ratchet mechanism, substantially as set forth.
- 20 7. In a device of the class described, circuit making and breaking mechanism, a wheel, teeth on said wheel, means on said wheel to engage and operate said circuit making and breaking means, radial spring-pressed pins so located radially around said wheel as to consecutively engage the teeth on said wheel when said pins are operated consecutively so that the last pin to be operated will cause said wheel to operate said circuit making and breaking mechanism, ratchet mechanism to prevent backward
- 25 30 35 40

movement of said wheel, and spring-pressed pins to release said ratchet mechanism, substantially as set forth.

6. In a device of the class described, a circular front plate of non-conducting material, a peripheral flange thereon, a central post secured in said plate adapted to act as an electric terminal, a rocking post pivoted in said plate, a switch lever secured on said post and adapted to contact with said central post to form a connection from said central post to said rocking post, an eccentric projection on the inner end of said rocking-post, an electric terminal secured to said plate in spaced relation to said eccentric projection, a swinging lever pivoted upon said plate and adapted to move into the space between said projection and said terminal and contact with both, a wheel supported on said central post, means to limit the movement of said wheel, a spring to operate said wheel in one direction, means on said wheel to engage and operate said swinging lever, inclined projections on said wheel, a plurality of spring-pressed pins mounted in said flange and adapted to engage consecutive teeth on said wheel when pressed in a prescribed order to move said wheel sufficiently to cause said swinging lever to close the break in the circuit between the eccentric projection and its adjacent terminal, so that the circuit will be completed from the central post to the terminal on said flange, mechanism to prevent said wheel from moving backward and radial spring-pressed pins mounted in said flange adapted to release said ratchet mechanism, substantially as set forth.

In testimony whereof I affix my signature.

BENJAMIN S. PUTTS.
